SAFETY LOCK FOR DOORS

Stanley J. Sage, Brookline, and Eugene H. Dana,
Canton, Mass.

Application May 25, 1956, Serial No. 587,272

1 Claim. (Cl. 292—347)

This invention relates to safety locking devices for door latch mechanisms, reference being had particularly to the push-button type locking devices of the class commonly employed in automobile doors wherein a push-button is secured in threaded relationship about an operating rod which projects vertically through the window frame of the automobile door and which constitutes a part of an actuating linkage for locking the main door latch mechanism.

As is well known, depressing the push-button serves to lock the latch mechanism and prevent accidental opening of the door, but the push-button is, of course, readily pulled up into a disengaged position and, from the standpoint of safeguarding children inside an automobile, is not a satisfactory safety lock. Various safety locking devices have been proposed to avoid the hazard involved but none of these, so far as we are aware, has been adopted commercially and there continues to be in present usage almost universally in car door latch constructions the simple push-button type of device described above.

It is a general object of the invention to improve push-button type locking devices for door latch mechanisms and to devise a special safety push-button construction which can be employed to take the place of a standard type of push-button. It is a further object of the invention to combine in a replacement push-button member effective safety locking features which are very conveniently placed in effect and which nevertheless require a combination of unlocking movements calculated to greatly reduce the danger of accidental release by children.

These and other objects and novel features may be more clearly understood and appreciated from the following description of preferred embodiments of the invention shown in the accompanying drawings, in which:

Fig. 1 is a view in cross-section of a door latch push-button construction designed to include a resiliently supported component;

Fig. 2 is a view in cross-section of the structure shown in Fig. 1 illustrating this structure in a displaced locking position; and

Fig. 3 is a perspective view showing in detail one of the component parts of the push-button construction shown in Figs. 1 and 2.

In the structure shown in these drawings, numeral 2b indicates fragmentarily a door, such as an automobile door, for example, in which there is provided a window frame section 4b. Numeral 6b denotes an operating rod forming a part of an operating linkage for locking a door latch mechanism of the class commonly installed in automobile doors.

The actual door latch mechanism which is to be safety

2

locked has not been shown in detail in the drawings, as it is believed that the illustration of the operating rod 6b is sufficiently representative of such a well-known structure. As is customary in most such door latch installations, the operating rod 6b extends upwardly through an opening 8b formed in the window frame 4b in a position such that it may conveniently receive a threaded push-button thereon.

Our present invention is based on the novel concept 10 of substituting for the conventional form of one-piece push-button ordinarily used, a special safety push-button construction which includes two separate sections capable of being secured to the operating rod of a door latch mechanism in such a manner that each section may be independently supported on the rod whereby one section is laterally displaceable with respect to the other section.

In accordance with a further aspect of the invention, we provide means for displacing one of the sections into a position in which it may be engage with an underside 20 of the window frame 4b and, by solidly securing this section to the operating rod, it is possible to effectively lock the door latch mechanism against accidental release.

Considering this safety push-button construction more 25 in detail, attention is first directed to the form of the invention illustrated in Figs. 1 and 2.

At its upper end, the tubular member 30 is formed with a flanged head 32 which is adapted in one position to seat against a shouldered portion 34 of a recess 36 in the top of the push-button section 10b. A spring 38 is located between the flange portion 32 and the shouldered portion 34 and normally seeks to hold the sleeve in the position shown in Fig. 1. However, the push-button section 10b may be raised upwardly against the action of the spring for a short distance and may 35 then be turned about its vertical axis. Rotative movement of the push-button section 10b causes displacement of a shouldered section 40 with respect to a complementary shouldered portion 42 formed on the push-button section 12b. This rotative movement, having 40 been carried out with the push-button sections in an extended position, a lateral displacement takes place and the lower push-button section is moved into locking engagement with the sill 4b and, at the same time, the shouldered portions 40 and 42 resist rotative movement 45 of the section 10b. To release this holding action of the shouldered and spring-held sleeve, it is necessary to lift the push-button section 10b upwardly and turn it in one direction so that the shouldered portions may be moved into a complementary seated position.

50 It will be evident from the foregoing description that we have provided a positive and effective safety lock which is particularly suited for use where it is desired to avoid accidental release by children. The component parts are conveniently constructed and assembled on the operating rod of standard type and require no changes in the door or latch mechanism.

55 While we have shown and described preferred embodiments of the invention, it should be understood that various other changes and modifications may be employed within the scope of the appended claim.

Having thus described our invention, what we claim is:
60 A push-button construction for use with the operating rod of a door latch mechanism comprising upper and lower push-button sections, said lower section having a tubular extension eccentrically disposed and secured therein, said extension being fixed to the operating rod,

the upper push-button section having the tubular extension resiliently and slidably supported therein, and said upper and lower push-button sections having adjacent surfaces relieved to form complementary engaging shoulders rotatable into and out of locking engagement with one another.
